(57) CLAIM

The ornamental design for an adhesive backed diaper packet, as shown and described.

DESCRIPTION

FIG. 1 is a front elevated view of an adhesive backed diaper packet showing my new design;

FIG. 2 is a back elevated view of the adhesive backed diaper packet;

FIG. 3 is a side elevated view of the adhesive backed diaper packet;

FIG. 4 is a top plan view of the adhesive backed diaper packet; and,

FIG. 5 is a bottom plan view of the adhesive backed diaper packet.

The broken line showing of the words “Peel & Stick” and “Stick Here to Seal” is for illustrative purposes only and forms no part of the claimed design.
